UNITED STATES PATENT OFFICE.

JOHN HANSEN, OF BETTENDORF, IOWA, ASSIGNOR OF FOUR TWENTY-FIFTHS TO
WILLIAM H. MARTIN, TEN TWENTY-FIFTHS TO T. S. CUNNINGHAM, AND ONE
TWENTY-FIFTH TO THOMAS McQUARRIE, ALL OF DAVENPORT, IOWA.

MECHANICAL GOLF INSTRUCTOR AND EXERCISER.

Application filed December 23, 1926. Serial No. 156,658.

My invention relates to a mechanical golf instructor and exerciser, and is of a type similar to that shown in my former application for Letters Patent of the United States, 5 dated October 14, 1926, and numbered 141,438. It has been discovered that the downward movement of a golf club in making a stroke is not exactly in the same plane as the upward movement, but that there is 10 a variation of a few inches, the downward stroke being the farthest to the front. The present invention has more special reference to the provision of a track for the guidance of the end of a golf club or stick which will 15 conform to this movement, and positively correct any inaccuracy in the stroke of the user.

In the drawings herein there is portrayed, so far as possible, a track of the kind mentioned, with the understanding that it is not exact in its details, but is designed to give as 20 close an idea of the device as possible, for use with the following specification.

In said drawings;

25 Fig. 1 shows the invention in perspective. Fig. 2 is a diagrammatic conception thereof.

Fig. 3 is a detail of the traveller for guiding the end of the club in its movement 30 along the track.

The reference number 1 indicates a frame, by which is supported a rear track of substantially oval shape, and a front track of similar shape. The rear track may be assumed to start at the lower part and extend 35 upwardly at 2 to the top, where it passes round a loop 3, and downwardly again at 4, the front track being a few inches in advance of the other track at 5. From this 40 point the front track curves upwardly again at 6, and is formed into a loop at 7, after which it is carried downwardly again at 8 to the place of beginning. The front and rear tracks are united at intervals by 45 braces 9.

Movable on the tracks is a traveller 10, by means of flanged rollers 11 in engagement with the edges of the rail of which the tracks are formed. Pivoted in the traveller is a 50 pin 12, with which is connected the end of a stick 13, similar in length and shape to a

golf stick, or a regular golf club may be substituted therefor, with a little adaptation.

The user of the device stands at a point centrally of the tracks and swings the stick 55 in the usual manner of a player making a stroke, the traveller moving along the tracks with little resistance. Starting at the bottom of the rear track he moves the traveller upwardly at 2, around the loop 3, and downwardly at 4, the end of the stick passing the rear track at 5, a little in front thereof. The stroke then continues upwardly along the track at 6 and around the loop 7, which practically completes the stroke, the stick 60 being brought downwardly again at 8 to the bottom of the rear track, in position for another stroke.

It is obvious that in passing round the loops the position of the traveller 10 will 70 be reversed, the stick 13 conforming readily to the positions thereof by reason of the pivotal arrangement of the pin 12.

For satisfactory operation at the lower part of the tracks the pin 12 should be supported at a point midway the tracks, as shown in Fig. 3. This will permit of the movement of the stick with the traveller on track 2, as in addressing the ball, and the return movement of the traveller on track 80 5, as in hitting the ball, without any undue strain on the club, or tendency to divert it from its true course.

What I claim, and desire to secure by Letters Patent, is:

1. A device of the class described, comprising a pair of substantially circular tracks, and golf stick guide slidable thereon, said tracks being provided at their upper sides with means for reversing the movement of said guide.

2. A device of the class described, comprising a frame, a pair of circular tracks supported by said frame in spaced relation, a traveller movable on said tracks, and loop 95 connections between said tracks at the upper side thereof, adapted to reverse the direction of movement of said traveller.

3. A device of the class described, comprising a pair of tracks supported in spaced 100 relation in substantially vertical planes, interconnected at their upper parts so as to

transfer a traveller moving thereon from the rear to the front track when moving in one direction, and from the front to the rear track when moving in the opposite direction.

- 5 4. In a device of the class described, a pair of tracks of substantially circular form, provided at their upper sides with reversing sections, a golf stick guide slidable on said

tracks, and a golf stick connection on said guide adapted to direct the movement of a 10 golf stick in a plane midway said tracks at the nearest approach thereof to the ground, when the guide is travelling on either of said tracks.

In testimony whereof I affix my signature.
JOHN HANSEN.
